STEERING HANDLE

Richard A. Munter, Mora, Minn., assignor to
Boatel Company, Inc., Mora, Minn.

Filed Jan. 22, 1970, Ser. No. 21,031

Term of patent 14 years

Int. Cl. D12—14

U.S. Cl. D14—30

FIG. 2

FIG. 1

FIG. 5

FIG. 4

FIG. 3

FIG. 1 is an orthographic projection taken on a line-of-sight perpendicular to the face of the steering wheel coincident with the steering axis thereof.

FIG. 2 is a front view of the steering handle.

FIG. 3 is a side view of the steering handle.

FIG. 4 is a top view of the steering handle.

FIG. 5 is a rear view of the steering handle.

I claim:

The ornamental design for a steering handle, as shown.
